ADJUSTABLE PISTON FOR INTERNAL COMBUSTION ENGINES

John Hlasney, Jr., New York, N. Y.

Application August 7, 1937, Serial No. 157,826

8 Claims. (Cl. 123—48)

This invention relates to new and useful improvements in an adjustable piston for internal combustion engines and the like.

More specifically, the invention contemplates the provision of an improved piston which may be used in connection with a cylinder to vary the compression of the cylinder and thus the horsepower characteristic thereof, by increasing or decreasing the capacity of the combustion chamber.

16. The invention is characterized by an adjustable piston consisting of piston sections provided with a means for urging them together, and still another means acting against one of the piston sections to oppose the first-mentioned means and so to separate the piston sections.

Still further the invention proposes the use of resilient elements mounted upon studs and acting between the ends of the said studs and portions of the piston sections for normally urging the sections together.

Still further the invention provides for a stem which is slidably mounted in a connecting rod for the piston and which is adapted to engage one of the piston sections and to be forced forward by a cam element which is mounted upon the crank rod or driving rod of the device.

Still further the invention proposes an expansion or resilient element which is to be mounted upon a stud and to act between the end of said stud and a portion of one of the piston sections for normally urging the sections together.

Another object of the invention is to provide for a stem which is slidably mounted on a connecting rod for the piston and which is adapted to engage one of the piston sections and to be forced forward by a cam element which is mounted upon the crank rod or driving rod of the device.

Still further the invention provides for a new type of crank rod to be used in conjunction with the device. This rod too consists of a crank having spaced radial arms with a rung rotatively mounted between the spaced arms.

For further comprehension of the invention, and of the objects and advantages thereof, reference will be had to the following description and accompanying drawings, and to the appended claims in which the various novel features of the invention are more particularly set forth.

50 In the accompanying drawings forming a material part of this disclosure:—

Fig. 1 is a transverse sectional view of the device.

Fig. 2 is a schematic perspective view of a portion of the device shown in Fig. 1.

Fig. 3 is a horizontal sectional view of a portion of the device shown in Fig. 1.

Fig. 4 is a sectional view similar to Fig. 1 but illustrating the parts thereof in a different position.

Fig. 5 is another sectional view similar to Fig. 1, illustrating the parts in still another position.

The adjustable piston for internal combustion engines and the like, according to this invention, 10 comprises a piston 10 which is slidably mounted in a cylinder with integral head 11. The piston 10 includes a top section 10^a and a bottom section 10^b having resilient means for normally urging them together. A crankshaft 12 is arranged 15 in the crankcase of the cylinders 11, and has a pair of spaced radial arms 13 fixedly attached to the crankshaft trunnion 12. A rung 14 is rotatively mounted between the radial arms 13, and has a connecting rod 15 indirectly freely 20 mounted thereon. The outer end 15^a of the connecting rod is pivotally mounted on the bottom section 10^b of the piston 10. When the crankshaft 12 is rotated the connecting rod 15 will move in and out of the cylinder 11 causing the 25 piston 10 to reciprocate therewith.

The means for urging the piston sections 10^a and 10^b together consists of lugs 16 mounted on the underside of the piston section 10^b. A pin 17 engages through an opening 18 in each lug 16 30 and through passages in the cylinder section 10^b, and threadedly engages into the piston section 10^a where it is firmly anchored. The end of each pin 17 is provided with a head 17^a, and an expansion spring 19 is coaxially mounted upon each 35 pin 17 and operates between the head 17^a and the lug 16 to urge the top section 10^a toward the bottom section 10^b.

A cam 20 is fixedly mounted on the rung 14, and there are plates 21 on either side thereof 40 which are rotatively mounted on the rung 14. A friction element 22 is located between each contacting face of the cam 20 and the plates 21 to keep these two elements in frictional engagement. The connecting rod 15 is provided with a forked 45 end 15^b which engages over the cam 20 and the plates 21, and is pivotally connected to the plates 21 by means of pins 23. Thus when the crankshaft 12 is turned the rung 14 will relatively turn in the spaced arms 13, and the cam 20 which is 50 fixed to the rung 14 will continuously remain in a normal position relative to the plates 21. The friction element 22 will engage the plates 21 and hold them in fixed relation with the cam 20 and with the aid of the forked portions 15^b of the con- 55

necting rod 15, will prevent these plates from rotating as the crank 12 and arms 13 are rotated.

A stem 25 is slidably mounted within the connecting rod 15 and is formed with an inner rounded end 25^a which engages the cam 20. The outer end 25^b of the stem 25 is provided with a rocker element 26 which engages a complementary curved portion 27 on the bottom of the top section 10^a to permit the rocker element 26 to assume different positions with relation to the crank 12. This is necessary because the connecting rod 15 is pivotally anchored to the bottom section 10^b and the slidable stem will move therewith making it necessary for the end 25^b to swing in an arc as the crank 12 reciprocates the piston 10. To permit this end 25^b to move in the arc, the rocker element 26 is provided, which engages the complementary curved portion 27.

The cam 20 has several cavities, but only a lower cavity 20^b, and raised cavity 20^d is used. When the end 25^a of the stem 25 is engaging a lower cavity 20^b, the piston sections associated therewith will be urged as closely together as they possibly can, but on the other hand when the end 25^a engages a raised cavity 20^d the stem 25 will be slid forward, within the connecting rod 15, forcing the outer section 10^a away from the inner section 10^b.

A means is associated with the device for changing the relative positions of the piston sections 10^a and 10^b. This means includes segmental friction members with cam outlines 28 and 28' which are fixedly mounted upon shafts 29 within enlarged portions 11^a of the casing of the cylinders 11. A means is provided for changing the relative position of the cam 20 with relation to the plates 21 to move the stem 25 forward within the connecting rod 15 to separate the sections 10^a and 10^b. This means includes cam elements 30 and 30' which are fixedly mounted on an extended end 14^a of the rung 14. Each shaft 29 extends from the cylinder 11 so that it may be adjusted to change the position of the elements 30 and 30'.

The shafts 29 are synchronized. There are sprockets 29^a mounted on the outer ends of the shafts and connected with a chain 29^b. One of the shafts 29 is provided with a drive pulley 29^c which is manually moved into its desired position. The arrangement is such that the friction members 28 may be operated as desired. They may be set in different phases or in the same phases, as desired.

The cam 20 is provided with projecting pins 20^e and 20^f (see particularly Fig. 1). These pins are adapted to limit turning of the cam 20 into two main positions. These pins are adapted to strike against the connecting rod 15 when they reach their positions. When the pin 20^e strikes against the connecting rod 15 the cam 20 is in a position in which the end 25^a of the stem 25 is in the low portion 20^b of the cam. This is the position illustrated in Figs. 1 and 2.

The second position of the cam 20 is one in which the cam turns anti-clockwise to a position in which the pin 20^f strikes against the connecting rod 15 and then the cam 20 will be in a position in which the end 25^a of the stem 25 is in the raised cavity 20^d, as shown in Fig. 5. The two positions of the cam 20 are obtained as follows: When the segmental cam friction member 28 at the right in Fig. 1 is turned through 180° to the position indicated by the dot and dash lines, then as the crankshaft 12 turns clockwise, the cam element 30 will strike the cam friction member

28, and means cause the rung 14 to turn clockwise to the position in which the pin 20^e will strike the connecting rod 15. After this position is reached the friction member 28 and the cam element 30, merely idle past each other. The cam 20 may be turned back to its original position by turning the cam friction member 28 back to its original position, as shown in Figs. 1 and 2, and turning the friction member 28' to the position indicated by the dot and dash lines. Then as the crankshaft 12 rotates clockwise the element 30' will strike against the cam friction element 28' and causes the rung 14 to rotate anti-clockwise, and thus turn the cam 20 back to its original position.

When the elements 30 and 30' are adjusted, they cause the rung 14 to turn within the arms 13 to move the cam 20 against the holding effects of the frictional elements 22. As the cam 20 is adjusted, the end 25^a of the shaft 25 will pass out of the lower cavity 20^b and into the raised cavity 20^d. When the end 25^a is within the raised cavity 20^d it will hold the top section 10^a separated from the bottom section 10^b as indicated by the dot and dash lines 10' in Fig. 1. The shifting of these elements 10^a and 10^b changes the compression space in the engine cylinder and thus the horse power and the fuel consumption characteristics of this engine.

The spaced radial arms 13 are formed with notched portions 13^a on their inner faces which permit these arms to pass over the forked portions 15^b of the connecting rod 15 as the crank shaft 12 rotates. Washer elements 36 are provided between the contacting faces of the plates 21 and the spaced arms 13, to keep them spaced from each other so that the arms 13 will not tend to rotate the discs 21, as the arms 13 are moved on the rung 14.

The operation of the device is as follows:

As the crankshaft 12 rotates, the outer end of the spaced arms 13 will move in an orbit A, (see Fig. 1), about the pivotal trunnion point of the crankshaft 12. As the rung 14 moves in this orbit, the cam 20 and the plate 21 will move therewith, by the piston 10 as it reciprocates within the cylinder 11.

When it is desired to change the relative positions of the sections 10^a and 10^b of the piston it is merely necessary to rotate the cam friction members 28 or 28' through 180°, so that their friction cam surfaces will engage the cam 30 or 30' during certain positions of the crankshaft 12, turning the rung 14, which in turn turns the cam 20, causing the end 25^a of the shaft 25 to pass out of the lower cavity 20^b and into the raised cavity 20^d, or vice versa, to shift the stem 25 forward or rearwards. As the stem 25 slides forward it presses against the rocker element 26, which in turn presses against the top section 10^a forcing this section away from the lower section 10^b against the holding action of the springs 19. The clearance and the capacity of the combustion chamber are thus reduced, and the compression increased.

When it is desired to move the sections 10^a and 10^b towards each other, it is merely necessary to turn the cam 20 back to its normal position to permit the end 25^a of the stem 25 to engage the lower cavity 20^b on the cam 20, permitting the springs 19 to draw the top section 10^a towards the lower section 10^b.

It is to be understood that instead of the chain drive 29^b, the two shafts 29 may be synchronized in any other suitable manner.

5 While I have illustrated and described the preferred embodiments of my invention, it is to be understood that I do not limit myself to the precise constructions herein disclosed, and the right is reserved to all changes and modifications coming within the scope of the invention as defined in the appended claims.

Having thus described my invention, what I claim as new, and desire to secure by United 10 States Letters Patent is:

1. In an internal combustion engine the combination of an adjustable piston slidably mounted in a cylinder head and comprising a top piston section and a bottom section, means for urging 15 said piston sections together, a crankshaft, a crank on said crankshaft having spaced radial arms and a rung rotative between said arms, a connecting rod pivotally connected to said bottom piston section and pivotally connected to said 20 rung, a cam fixedly mounted on said rung, a stem slidably mounted on said connecting rod and connected to said piston by engaging said top piston section and having its inner end abutting said cam, means for adjusting said cam relative 25 to said stem whereby said crank may be rotated to reciprocate said piston, and said cam adjusted to move said stem to change the relative position of said piston sections.

2. In an internal combustion engine the combination of an adjustable piston slidably mounted in a cylinder head and comprising a top piston section and a bottom section, means for urging 30 said piston sections together, a crankshaft, a crank on said crankshaft having spaced radial arms and a rung rotative between said arms, a connecting rod pivotally connected to said bottom piston section and pivotally connected to said rung, a cam fixedly mounted on said rung, a stem 35 slidably mounted on said connecting rod and connected to said piston by engaging said top piston section, and having its inner end abutting said cam, means for adjusting said cam relative to said stem whereby said crank may be rotated to reciprocate said piston, and said cam adjusted to move said stem to change the relative position 40 of said piston sections, said means for urging said piston sections together comprising a lug fixedly mounted on the bottom section and having an aperture therethrough, a pin engaged through said aperture and having one of its ends anchored in said top section, and a spring coaxially mounted on said pin and operating between said lug and a headed portion of said pin, for urging said top section toward said bottom section.

3. In an internal combustion engine the combination of an adjustable piston slidably mounted in a cylinder head and comprising a top piston section and a bottom section, means for urging 45 said piston sections together, a crankshaft, a crank on said crankshaft having spaced radial arms and a rung rotative between said arms, a connecting rod pivotally connected to said bottom piston section and pivotally connected to said rung, a cam fixedly mounted on said rung, a stem 50 slidably mounted on said connecting rod and connected to said piston by engaging said top piston section, and having its inner end abutting said cam, means for adjusting said cam relative to said stem whereby said crank may be rotated to reciprocate said piston, and said cam adjusted to move said stem to change the relative position 55 of said piston sections, said pivotal connection between said rung and said connecting rod comprising plates rotatively mounted on said rung.

on both sides of said cam, and a forked end engaging over said cam and said plates, and pivotally connected to said plates.

4. In an internal combustion engine the combination of an adjustable piston slidably mounted in a cylinder head and comprising a top piston section and a bottom section, means for urging 5 said piston sections together, a crankshaft, a crank on said crankshaft having spaced radial arms and a rung rotative between said arms, a connecting rod pivotally connected to said bottom piston section and pivotally connected to said rung, a cam fixedly mounted on said rung, a stem 10 slidably mounted on said connecting rod and connected to said piston by engaging said top piston section, and having its inner end abutting said cam, means for adjusting said cam relative to said stem whereby said crank may be rotated to reciprocate said piston, and said cam adjusted to move said stem to change the relative position 15 of said piston sections, said pivotal connection between said rung and said connecting rod comprising plates rotatively mounted on said rung on both sides of said cam, and a forked end engaging over said cam and said plates, and pivotally connected to said plates.

20 25 30 35 40 45 50 55 60 65 70 75

5. In an internal combustion engine the combination of an adjustable piston slidably mounted in a cylinder head and comprising a top piston section and a bottom section, means for urging 30 said piston sections together, a crankshaft, a crank on said crankshaft having spaced radial arms and a rung rotative between said arms, a connecting rod pivotally connected to said bottom piston section and pivotally connected to said rung, a cam fixedly mounted on said rung, a stem 35 slidably mounted on said connecting rod and connected to said piston by engaging said top piston section, and having its inner end abutting said cam, means for adjusting said cam relative to said stem whereby said crank may be rotated to reciprocate said piston, and said cam adjusted to move said stem to change the relative position 40 of said piston sections, said means for adjusting said cam comprising a shaft rotatively mounted in an enlarged portion of said cylinder head, a friction member on said shaft, and a cam on an extended end of said rung, and adapted to be engaged by said friction member when it is rotated through 180°.

6. In an internal combustion engine the combination of an adjustable piston slidably mounted in a cylinder head and comprising a top piston section and a bottom section, means for urging 55 said piston sections together, a crankshaft, a crank on said crankshaft having spaced radial arms and a rung rotative between said arms, a connecting rod pivotally connected to said bottom piston section and pivotally connected to said rung, a cam fixedly mounted on said rung, a stem 60 slidably mounted on said connecting rod and connected to said piston by engaging said top piston section, and having its inner end abutting said cam, means for adjusting said cam relative to said stem whereby said crank may be rotated to reciprocate said piston, and said cam adjusted to move said stem to change the relative position 65 of said piston sections, said cam being provided with a lower cavity adapted to be engaged by said stem for permitting said first mentioned means to draw said top section towards said bottom section.

7. In an internal combustion engine the combination of an adjustable piston slidably mounted in a cylinder head and comprising a top piston section and a bottom section, means for urging said piston sections together, a crankshaft, a crank on said crankshaft having spaced radial arms and a rung rotative between said arms, a connecting rod pivotally connected to said bottom piston section and pivotally connected to said 10 rung, a cam fixedly mounted on said rung, a stem slidably mounted on said connecting rod and connected to said piston by engaging said top piston section, and having its inner end abutting said cam, means for adjusting said cam relative 15 to said stem whereby said crank may be rotated to reciprocate said piston, and said cam adjusted to move said stem to change the relative position of said piston sections, said cam being provided with a lower cavity adapted to be engaged by said stem for permitting said first mentioned 20 means to draw said top section towards said bottom section, said cam being provided with a raised cavity adapted to be engaged by the inner end of said stem to move it forward within said 25 connecting rod to urge said top piston section

away from said bottom piston section against the normal action of said first mentioned means.

8. In an internal combustion engine the combination of an adjustable piston slidably mounted in a cylinder head and comprising a top piston section and a bottom section, means for urging said piston sections together, a crankshaft, a crank on said crankshaft having spaced radial arms and a rung rotative between said arms, a connecting rod pivotally connected to said bottom 10 piston section and pivotally connected to said rung, a cam fixedly mounted on said rung, a stem slidably mounted on said connecting rod and connected to said piston by engaging said top piston section, and having its inner end abutting said cam, means for adjusting said cam relative 15 to said stem whereby said crank may be rotated to reciprocate said piston, and said cam adjusted to move said stem to change the relative position of said piston sections, said cam being provided 20 with rollers on the portions which abut the inner end of said stem to decrease wear and tear between these elements.

JOHN HLASNEY, JR. 25
